CROSSING PROTECTIVE SYSTEM

William G. Miller, Detroit, Mich., assignor to
 Grade Crossing Guard Corp., Memphis, Tenn.,
 a corporation of Tennessee

Application February 10, 1937, Serial No. 125,081

20 Claims. (Cl. 39—6)

The present invention relates to protective devices of the barrier type, that is, of the type in which a retractable and projectable barrier is supported in a pit in a roadway or other area to be protected, and may be automatically or otherwise projected to a blocking position and retracted therefrom under predetermined operating conditions.

Objects of the present invention are to provide an improved barrier protective system of the above identified type, so constructed and arranged as to insure proper operation under all conditions, and which may be relatively economically manufactured, assembled, and installed.

More specific objects of the present invention are to provide a protective system of the above stated character, embodying a plurality of barrier devices, the projecting and retracting movements of which are effected by spring mechanism associated therewith; to provide such a system in which the projecting and retracting mechanism embodies an axially movable shaft connected to each barrier through the just mentioned springs, movement of which in one direction projects each barrier and movement of which in the other direction retracts each barrier; and to provide such a system embodying supplemental continuously acting balancing spring mechanism which acts to urge each barrier upwardly.

Further objects are to provide such a system in which the individual barriers are pivotally connected to the associated casings, the pivotal connections being such as to floatingly restrain the barriers against movement within the casing; and to provide such a system in which the barriers and casings are provided with cooperating abutments, in conjunction with the floating barrier supports, which act to directly transmit impact forces from each barrier to the casing.

Further objects of the present invention are to provide a barrier system as above described, including improved means to enable the retracting mechanism to apply a positive lifting force to the barriers under certain circumstances; and to provide such a system in which the just stated force is applied through one or more cams associated with the barrier crank shafts and disposed to engage the barriers and positively force the same upwardly.

A further object of the present invention is to provide a barrier system of the above stated type in which the connections between the barriers and the projecting and retracting mechanism are of a lost motion type, permitting the barriers to be forcibly depressed against the forces of the lifting

springs, independently of the positions of the reTRACTING elements.

Further objects of the present invention are to provide a barrier system of the above stated type embodying an improved driving unit, embodying means to retain the barriers in any one of a plurality of positions against the forces of the lifting mechanism individual to the barriers; and embodying limit switch and timing mechanism controlled in accordance with the barrier position for automatically controlling the operating cycles of the barriers; and to provide such a system in which the just mentioned elements cooperate to automatically bring the barriers to rest, for a predetermined period, when the barriers reach an intermediate point in a projecting movement.

With the above and other objects in view, which appear in the following description and in the appended claims, preferred but illustrative embodiments of the present invention are shown in the accompanying drawings, throughout the several views of which corresponding reference characters are used to designate corresponding parts, and in which:

Figures 1 and 2, taken together with Fig. 2 considered as positioned to the right of Fig. 1, comprise a general view in elevation of the crossing barrier of the present invention;

55

Fig. 14 is a schematic diagram of control circuits which may be used to control the motor associated with the ram mechanism of Figs. 11 and 12.

Referring first to Figs. 1, 2, 3, 4 and 5, each barrier device comprises generally a barrier 20 which is projectably and retractably supported in a casing 22 formed of an I-beam 24 and a channel beam 25 connected together by transverse ribs 26. The casing is suitably imbedded in a pit formed in the roadway with which the device is associated. As shown in the diagrammatic view, Fig. 3, in using the invention in connection with highways, each crossing installation preferably includes at least four of the devices, two thereof being mounted at each side of the protected intersection. Each of the illustrated traffic lanes A and B (Fig. 3) is thus provided with two of the devices, one thereof being at the entering side of the intersection and the other thereof being at the departing side of the intersection. In certain instances, it is found practicable to protect only the entering side. Generally, however, it is found advisable to protect each lane at both the entering and departing sides, in order to prevent an oncoming vehicle from avoiding the barrier by swerving out of the regular lane of travel. All barriers at each side of an intersection are connected together for common control by a single drive unit 28 individual to such side.

In Fig. 3 also, it is assumed that each device is sufficiently wide to protect its entire associated lane. To accommodate the devices to lanes of greater width, it will be appreciated that the lengths of the individual devices may be increased. Alternatively, the devices may be made in a variety of different lengths, and two or more thereof connected in end to end relation to accommodate roadways of too great a width to be handled conveniently by a single device per lane. A feature of the present construction is the ready adaptability of the barriers for such end to end duplication.

Each barrier 20 is preferably formed as a single, elongated, shell-like casting, generally triangular in shape in vertical transverse section, the back of which is enclosed to form a part of the roadway when the barrier is in depressed position, and the generally arcuate front of which is enclosed to form an impact portion. The ends are also preferably enclosed to constitute protective skirts. The under side is preferably open to accommodate the operating elements associated with the barrier. Each enclosing end skirt 30 of each barrier 20 lies closely adjacent the associated end 32 of the casing 22 and with the overhanging flange 31 of each barrier cover, acts to prevent dirt and other foreign matter from falling into the casing when the barrier is in the raised position. The forward skirt portion 34 lies closely adjacent the forward, upper edge lip 36 of the casing when the barrier is in raised position and performs a corresponding function. The rectangular dimensions of each barrier 20 and casing 22 are such that in the retracted position, only very small spaces are left around the barrier edges, thus minimizing the entrance of dirt and other foreign matter into the casing.

The impact portion 37 of each barrier is preferably reversely formed, to present an arcuate engaging surface. The arcuate curvature is preferably such that a substantial area is engaged by a tire of a vehicle which engages the barrier. The inclination of the engaging portion 37 in

its relation to the height of the barrier, is determined in accordance with the disclosure of the co-pending application of Edward S. Evans, Serial No. 33,037, filed July 25, 1935, and assigned to the assignee of the present application. As disclosed and claimed in this co-pending application, by properly relating the height and inclination of the engaging face of the barrier, a construction results which, when engaged by a vehicle, forces the front end of the vehicle upwardly with a force sufficient to substantially counteract the forward thrust which would otherwise be given an occupant of the vehicle. Vehicles may thus be stopped by the barriers without injury to occupants of the vehicles.

*Supporting relation between barrier and casing—
Figs. 1, 2, 4 and 5*

It will be appreciated that, in operation, crossing barriers of the type in question are subjected to an extremely heavy duty. They are required to successfully withstand the impact forces of vehicles of widely varying weights, and traveling at widely varying speeds, and are required to bring said vehicles to rest without permitting the passage thereof into the protected intersection. Each barrier and casing is, accordingly, subjected to tremendous impact forces.

The forces involved in the successful operation of a protective device of the kind in question have shown it to be inadvisable to utilize a usual hinging relation between each barrier and its supporting casing, and in the present instance, the hinge connection between each barrier and its casing is illustrated as resiliently constructed, in accordance with the arrangement disclosed in the Goodman Patent No. 1,878,234, granted September 20, 1932.

As described in detail in the Goodman patent, each barrier 20 is provided, in suitably distributed relation along its back, with a plurality of bearings 40, each of which receives a conventional hinge pin 42. The ends of each hinge pin 42 project beyond the ends of the associated bearing 40, and provide support for one end of each of two "goose-neck" springs 44. The other end of each spring 44 is secured to the rear casing beam 25, by a bar 46 or in any other suitable way. In the present instance four pairs of springs 44 are illustrated and it will be appreciated that these four pairs cooperate together to resiliently maintain the rear edge of the associated barriers 20 at substantially the elevation shown in the various figures, in which elevation the upper barrier surface forms a continuation of the roadway. In such normal position, a foot 48 formed at the base of the barrier rests upon the spaced transverse beams 26, and the forward upper edge 50 of the barrier lies in slightly spaced relation above the previously mentioned member 36 associated with the forward casing beam 24. In order to provide a firm and positive limit to downward movement of the rear edge of the barrier, the under side thereof is formed to cooperate with the rest upon an abutment 52 which is secured to the rear casing beam 25. Normally the rear edge of the barrier is maintained in slightly spaced relation to the abutment 52 by the previously mentioned springs 44.

Raising and lowering mechanism—Figs. 1, 2, 4 and 5

In accordance with the present invention, each barrier is subjected to a positive moving force to effect both the projecting and the retracting

movements thereof, and in addition, is subjected to a continuously acting balancing force tending to cause the carrier to move to the projected position. The balancing force thus applied is insufficient to effect an actual lifting or projecting movement, but substantially compensates for the weight of the moving parts of the barrier, thus reducing the load to which the lifting mechanism is subjected.

Considering first the balancing mechanism, a shaft 50 is rotatably supported within bearing bosses 53 adjacent the rear wall 25 of the casing 22, and is normally maintained in a non-rotative position by ratchet mechanism 54 associated therewith as described in more detail below. The shaft 50 carries two helical springs 56 which act to urge the barrier 20 in a projecting direction. One end of each spring 56 is secured in a fixed rotative position relative to the shaft by a collar 58 individual thereto and suitably fixed upon the shaft 50 in non-rotative relation thereto. The connection between each collar 58 and its associated spring end is made by providing each collar with a lug 60, around which the hooked end 62 of the spring may be passed.

The other end of each spring 56 is connected (Fig. 5) to a lifting arm 70, which is rotatably journaled in axially fixed position on the shaft 50, and is connected to the barrier 20 through a link 72 of adjustable length. One end of the link 72 is pivotally connected to the barrier by a pin 14 received in a clevis 76, and the other end thereof is connected to the link 70 by a pin 78. With this arrangement, as will be appreciated, rotation of link 70 in a clockwise direction as viewed in Fig. 5 is accompanied by a projecting movement of the barrier 20 and a reverse rotation is accompanied by a lowering or retracting of the barrier 20. The connection between the left-hand spring 56, that is, the spring 56 shown in Fig. 1, is made by simply hooking the bent end 80 of the spring around the arm 70. The connection between the right-hand spring 56, that is the spring shown in Fig. 2, is made through an arm 82 which forms a part of a collar 84 which is freely rotatable relative to shaft 50 and to which the end of the spring is connected in the manner described with reference to the connection between the spring end 80 and the arm 70.

Each ratchet element 54, one of which is shown in more detail in Fig. 2A, comprises a toothed element 98 formed integrally with a turning element 92. A dog 94 is pivoted by a pin 96 to a bracket 98 which in turn is suitably secured to the rear casing wall. The nose of the dog is continuously urged into meshing relation to the ratchet by a tension spring 100. As will be appreciated, a suitable tool may conveniently be inserted in one of the openings 102 formed in the turning element 92, to rotate the ratchet mechanism 54 and the shaft 50. Rotation thereof in the clockwise direction as viewed in Fig. 2A winds up both spring 56 and increases the normal tension thereof. Rotation thereof in the counter-clockwise direction on the other hand, which may be effected by manually releasing the dog 94, reduces the tension to which the springs 56 are subjected. Normally, as will be understood, each dog 94 retains the associated ratchet mechanism, and consequently the shaft 50, against rotation in the unwinding direction.

With the above described arrangement, it will be appreciated that the springs 56 act to apply a continuous lifting force to the barrier 20, the magnitude of which is determined by the initial

stress to which the springs are subjected. Preferably, this initial stress is such that the springs substantially counterbalance the weight of the moving parts of the barrier but are ineffective to cause a lifting movement thereof.

5

Considering now the elements for applying a positive lifting and retracting force to each barrier 20, a slide shaft 110 is disposed in longitudinally extending relation within the barrier and is supported for axial sliding movement by a plurality of bearing members 112, which may conveniently be supported upon the previously described transverse ribs 26. One end of the shaft 110 is connected to the hereinafter described drive unit 28, and the other end, shown as broken away, may extend to a second barrier for connection thereto in the manner shown for the illustrated barrier. A single drive unit 28 and actuating shaft 110 may thus be used to actuate a plurality of otherwise independent barriers.

The shaft 110 is provided with a pair of collars 118 and 120, fixed thereon against axial movement relative thereto, and a slidable collar 122 which is positioned intermediate the two collars 118 and 120. A compression spring 124 is received between the collars 118 and 122 and a similar compression spring 126 is received between the collars 122 and 120. The springs 124 and 126 are disposed to exert balanced forces on the collar 122 and maintain it in the illustrated or retracted position when the actuating shaft 110 is in the corresponding illustrated position. A pin 128 projects from each side of the collar 122, and is received between the two legs 130, 132 which are provided at the bifurcated end of a bell crank 134. The bell crank 134 is suitably journaled upon a trunnion 136 which in turn is supported upon a bearing bracket 138, stationary supported in the barrier casing 22. The other end of the bell crank 134 is universally connected by a ball joint 140 to one end of a link 142, the other end of which is connected to the barrier 20 by a corresponding ball joint 144.

In operation, in order to effect a lifting movement of the barrier 20, the shaft 110 is caused to move to the left as viewed in Figs. 1 and 2, carrying with it the two collars 118 and 120. The movement of collar 120 causes a corresponding movement of the compression spring 126, which spring subjects the slidable collar 122 to a moving force proportional to the degree of compression of spring 126. The resultant movement of collar 122 causes a rotation of the bell crank 134 in the clockwise direction as viewed in Fig. 1, correspondingly moving the barrier 20 in the projecting direction. To effect a retracting movement of the barrier, the shaft 110 is caused to move to the right, bringing the collars 118 and 120 to the illustrated position. The movement of collar 118 causes corresponding movement of the spring 124, which accordingly acts through collar 122 to effect a counter-clockwise rotation of the bell crank 134, returning the barrier 20 to the illustrated retracted position.

65

It will be appreciated, accordingly, that the barrier 20 is connected to the shaft 110 through the two springs 124 and 126, which connection is a yieldable or resilient lost motion connection. Thus, with shaft 110 in either the fully or partially projected position, barrier 20 may be forcibly retracted against the combined lifting forces of the spring 126 and the balancing spring 56. Similarly, with shaft 110 in either the fully or partially retracted position, barrier 20 may

70

75

be forcibly retained in a partially or entirely projected position. Obstructions to the barrier movement in either projecting or retracting direction accordingly do not cause damage to or interfere with the operation of the slide shaft 110. Upon release of the obstructing force, however, the barrier immediately moves to the position corresponding to the then position of the shaft 110.

10 *Ice breaking mechanism—Figs. 1, 2, 4 and 6*

In instances where the barrier remains in the retracted position for long periods of time, and under severe weather conditions, it may be expected that more or less ice or other foreign matter will accumulate between the barrier and the casing therefor, which may oppose the projecting movement of the barrier with a force in excess of the lifting force applied thereto through the lifting spring 126 and the balancing spring 56. In accordance with the present invention, means are provided to initially supplement the force of the lifting and balancing springs by a force which is applied directly to the barrier by the drive mechanism.

25 In accordance with the illustrated embodiment, this additional initial lifting mechanism comprises a pair of cams 150 and 152, positioned in suitably distributed relation along the barrier so as to apply corresponding forces to both ends of the barrier. The cams 150 and 152 are formed integrally with bell crank members 154 and 156, which are pivoted upon trunnions 158 and 160. The trunnions in turn are supported in clevices 162 and 164 which may conveniently be secured to the previously mentioned transverse ribs 26. The positioning and proportioning of the cams 150 and 152 is such that in their normal retracted positions, they occupy positions immediately below but in slightly spaced relation to the foot 48 of the barrier (Fig. 6).

40 The other end of each of the bell cranks 154 and 156 are formed as clevices 170 and 172 respectively, the opposite legs of which are bifurcated and receive pins 174 and 176 which project from collars 178 and 180 respectively. The collars 178 and 180 are secured to shaft 110 in axially spaced relation to each other.

45 With this arrangement, as will be appreciated, a movement to the left of shaft 110 as viewed in Figs. 1 and 2, results in a counter-clockwise rotation of both of the bell cranks 154 and 156 and consequently of the lifting cams 150 and 152. The proportioning of the parts is such that the initial projecting movement of shaft 110 moves the cams 150 and 152 from the initial slightly spaced position thereof into positions of positive engagement with the barrier 48 and finally out of engagement therewith. During the period of engagement, the foot 48 and consequently the barrier 20 is subjected to a positive lifting movement determined by the throw of the cams 150 and 152, which positive lifting movement serves to free the barrier from any accumulated ice or foreign material and release it for continued movement under the influence of the lifting spring 126 and balancing springs 56. The feature of moving the cams 150 and 152 out of cooperative relation to the foot 40, after the just stated initial movement of the slide shaft 110, positively prevents the cams from being forcibly struck by the barrier foot 48 in the event the barrier is depressed by an external force during a raising movement of the shaft 110.

Driving mechanism—Figs. 1, 7, 8 and 9

In the preferred practice of the present invention, the drive unit 28 comprises a gear case 190, one face of which is provided with a flange 192 by which it may be connected to a suitable supporting structure 194, the other face of which is enclosed by an elongated bonnet 196. A supplementary open ended shell 198 is secured to the opposite side of the supporting structure 194, and encloses the pivotal connection 200 between the end of the reciprocating screw 202 and the end of the slide shaft 110. The case or housing 190 is formed to receive roller bearing elements 191 and 193 which rotatably journal a worm wheel 204, the internally threaded hub of which receives the reciprocating screw 202. The worm wheel 204 is disposed in continuous mating relation to a cooperating worm 206 which is carried by a drive shaft 208. The shaft 208 is rotatably journaled in casing 190, within roller bearing assemblies 210, and one end thereof projects outwardly of the casing and is suitably connected as by a flexible coupling 212 to the shaft of a suitable prime mover illustrated as an electric motor 214. The other end of the shaft 208 may also extend externally of the casing 190 and be arranged, if desired, for manual actuation.

20 The shaft 208 is provided with a supplemental worm 220, which meshes with a worm wheel 222 carried by a vertically disposed shaft 224. The shaft 224 is suitably journaled in the casing 190 within bosses 226 and 228, and at its upper end, is provided with a worm 230 which meshes with a worm wheel 232 carried by a horizontally extending controller shaft 234. The shaft 234 is 35 journaled within the casing 190 within bosses 236 and 238 and the end thereof extends outwardly of the casing for connection, as by a flexible coupling 240, to the shaft 242 of a suitable electrical controller 244. The construction and operation 40 of the controller 244 is described hereinafter with reference to the control diagram of Fig. 10.

With the described arrangement, it will be appreciated that the rotation of motor 214 in one direction or the other effects a corresponding 45 axial movement of the screw 202 through the medium of the gears 206 and 204. Such rotation similarly effects a rotative movement of shaft 242 of the controller 244 through the medium of the gears 220, 222, 230 and 232. The movement of 50 the controller 244 controls the starting and stopping of the motor 214 as hereinafter described, and the axial movements of the member 202 are transmitted as corresponding axial movements of the shaft 110. The movements of shaft 110 as 55 previously described effect the raising and lowering of the barrier. It will be noted that the gearing relation of the drive unit 28 is such that axial forces applied to the drive unit through the shaft 110 are ineffective to effect a reverse driving movement of the drive unit. Accordingly, the drive unit is effective to lock the shaft 110 in any 60 positions of the parts in which motor 214 may be brought to rest.

65 *Control system for driving motor—Fig. 10*

In accordance with the preferred operation of the barriers, the driving motor 214 described with reference to Figs. 7, 8 and 9 is actuated to cause 70 the associated barriers to move upwardly from the retracted position to an intermediate or warning position and stop, and remain at this warning position for a predetermined timing interval. The warning position of the barriers 75

may be one in which they are sufficiently high above the roadway to expose the warning letters on the face thereof and thus afford a signal to approaching vehicles but, on the other hand, not high enough to constitute a substantial obstruction to the passage thereover of vehicles. At the expiration of the predetermined time interval, the motor 214 is preferably re-started and caused to move the associated barriers to the fully projected position and retain them in such projected position until the traffic or other road condition has been cleared.

As soon as the traffic or road condition has cleared itself, it is preferred that the barrier immediately returns to the retracted positions in which position they are retained at rest by the drive unit until a subsequent operation thereof is necessary.

In instances where the barriers are used in connection with rail-highway crossings, as described in the Goodman patent, the approach of a train to the intersection may be relied upon to initiate the barrier projecting movements and the departure of the train from the crossing may be relied upon to initiate the retracting movements. Similarly, in instances where the barriers are used in connection with lift bridges, or the like, the projecting movements of the barriers may be initiated either manually or automatically at a predetermined interval prior to the beginning of the bridge lifting movement, and the barrier retracting movements may be initiated automatically upon the arrival of the bridge at its lowered position.

Fig. 10 shows an illustrative control system for the motor 214 associated with the drive unit of Figs. 7, 8 and 9, which drive unit as previously stated may be common to all of the barriers positioned at one side of a protected intersection. It will be appreciated that a duplicate drive unit is provided for barriers at the opposite side of an intersection, such as shown in Fig. 3, and that a control system similar in all respects to the control system of Fig. 10 may be provided for such additional drive unit. In Fig. 10, a switch US is provided to initiate the barrier projecting movements and an illustrative switch DS is provided to initiate the retracting movements. As will be appreciated, the switches US and DS may be operated either manually or automatically, it being assumed in the illustrated instance that the switch US is manually operated and that the switch DS is automatically operated, as by the return of a lift bridge to the lowered position thereof, or by the clearing of the rail intersection of Fig. 3. The direction of operation of the motor 214, in response to the switches US and DS is selectively controlled by a pair of reversing switches R1 and R2, the controller contacts C1, C2 and C3 and a time relay T.

The controller contacts C1, C2 and C3 may be embodied within the previously described controller 244 in any suitable way well known in drum controllers, the relation being such that the controller contact C1 is closed when the drive unit is in a position corresponding to the retracted position of the associated barrier or barriers, and remains closed during movement of the drive unit to a position corresponding to the warning position of the barriers, opens at such warning position and remains open until the drive unit again reaches the warning position during the reverse movement thereof. The controller contact C2 is normally open, but is closed when the drive unit reaches a position corresponding to the

warning position and remains closed until the drive unit reaches a position corresponding to the fully projected position. The remaining controller contact C3 is normally open, but re-closes just after the drive unit starts a projecting movement and remains closed until the drive unit, moving in the reverse direction, reaches a position corresponding to the retracted position. The remaining details of the control system may best be understood with reference to a description of the operation of the system as a whole.

Referring particularly to Fig. 10 and having in mind the structure shown in the remaining figures, it will be appreciated that the switch US normally occupies an open position, and that the switch DS normally occupies a closed position, indicating that the intersection or traffic situation is clear. In order to place the barriers in operation, the switch US may be closed, to thereby complete a circuit for the reversing switch R1 and for the time relay T. The circuit for the reversing switch R1 extends from the positive line conductor through the switch US, controller contact C1 which is now closed and thence through the coil of switch R1 and a normally closed interlocking contact R2b to the negative line conductor. The circuit for the time relay T extends through the switch US and thence through the time relay coil and normally closed contact R2a to the negative line.

Upon completion of the circuit for the coil thereof, reversing switch R1 is actuated to the closed position, in which the contacts R1b, R1c, and R1d thereof are closed, and in which the interlocking contact R1a thereof is open. The contact R1a is included in a circuit of the reversing switch R2, and prevents closure of this switch as long as switch R1 is closed. The two contacts R1b and R1c complete a conventional reversing circuit for the armature of the drive motor 214. The contact R1d completes a circuit for the field winding 214f of the motor 214. It will be appreciated that the switch R1 may be so arranged that the contact R1d is closed slightly in advance of the closure of contacts R1b and R1c, thus insuring that the field of the motor is in a fully energized condition at the time that the armature circuit thereof is completed.

Completion of the just mentioned field and armature circuits of motor 214 causes this motor to start in operation in a direction to cause the slide shaft 110 of Figs. 1 and 2 to move in the leftward or projecting direction. This movement of the drive shaft 110 as previously described, results in a projecting movement of each barrier 20 connected to the drive shaft.

Energization of the coil of the time relay T, through the previously traced circuit, causes this relay to close its upper contact Ta, which contact completes a holding circuit for the coil of the reversing switch R1 (subject to the controller contact C1), and also completes a holding circuit for the coil of the time relay T. Thus, the starting switch US need be only momentarily closed, in order to initiate the operating sequence. Energization of the coil of the time relay T also initiates a closing movement of the contact Tb thereof which contact, however, is subject to the action of suitable time delay mechanism (not shown) which delays the closure thereof for a predetermined interval.

As rotation of the drive motor 214 continues, and brings the drive shaft 110 to a position corresponding to the warning position of the barriers, the controller contact C1 opens, interrupting the

just traced holding circuit for the reversing switch R1, and causing this switch to resume its illustrated open position. This action, as will be appreciated, interrupts the previously described 5 armature and field circuits for the motor 214, bringing this motor to rest with the barriers in the warning position.

The time interval provided in the closing movement of the time relay contact Tb exceeds 10 the time required for the barriers to reach the warning position to an extent determined in accordance with the period throughout which it is desired that the barriers shall remain at the warning position. At the expiration of this pre- 15 determined period, the time relay contact Tb closes and re-completes a circuit for the coil of the reversing switch R1. This re-completed circuit extends through the now closed controller contact C2, contact Tb and thence through the 20 coil of the reversing switch R1 to the negative line as previously traced. Upon completion of this circuit, reversing switch R1 re-closes and re-starts the drive unit motor 214 in the original direction, which action results in a further projecting movement of the barriers 20 connected thereto.

As the drive motor 214 continues in operation, and brings the barriers 20 connected thereto to the fully projected position, the controller contact C2 is actuated to the open position, interrupting the previously traced circuit for the reversing switch R1. This action as before, brings the drive motor 214, and consequently all barriers connected thereto, to rest in the fully projected 30 position. The barriers remain in this position until a circuit is completed to effect reverse movement of the barrier.

As stated above, in connection with railway crossings, etc., the re-starting of the drive unit 40 to effect a retracting movement of the barrier may be effected in response to the departure of a train from the protected crossing. In the illustrated system, a contact DS is provided which may be regarded as occupying the closed position 45 as long as the roadway or other way associated with the barriers is in a clear condition; and as occupying the open position except under such clear conditions.

Assuming a clear condition, contact DS resumes 50 the closed position and completes a circuit through the now closed controller contact C3 for the coil of the reversing switch R2. Upon completion of this circuit, the switch R2 moves to the closed position, opening its contacts R2a and R2b, 55 and closing its contacts R2c, R2d and R2e. The opening of contact R2a interrupts the circuit for the time relay T, causing this relay to resume the illustrated position in readiness for a subsequent timing operation. The opening of contact R2b 60 prevents completion of a circuit for the reversing switch R1 even though, during the retracting movement, the controller contacts C1 and C2 may be moved to the closed position. Closure of contacts, R2c, R2d, and R2e completes armature and 65 field circuits for the motor 214, which correspond to the previously described armature and field circuits with the exception that the armature of the motor is connected across the line conductors in reverse relation. The closure of reversing 70 switch R2, accordingly, causes the motor 214 to rotate in a retracting direction, and effect movement of the drive shaft 110 to the right, as viewed in Figs. 1 and 2.

As the movement of the drive motor 214 brings 75 the drive shaft 110 to a position corresponding to

the retracted position of the barriers connected thereto, the controller contact C3 moves to the open position, interrupting the previously traced circuit for the reversing switch R2 which thereupon resumes the illustrated open position in which the armature and field circuit for the motor 214 are interrupted. Accordingly, the drive unit is brought to rest in a position corresponding to the retracted position of the barrier and remains in the rest position until the starting switch US 10 is again closed.

It will be noted that the controller contacts C1 and C2 are closed throughout portions of the return movement of the associated drive unit, which action is however without effect in view 15 of the fact that the associated circuits are otherwise interrupted. Similarly, during the projecting movement of the associated drive unit, the controller contact C3 is closed which action, however, is without effect in view of the open condition 20 of the reversing contact R1a.

As previously stated, one complete drive unit is preferably provided for all of the barriers at one side of each intersection or protected point, and a similar drive unit is provided for the barriers at the other side of the intersection or protected point. It will be appreciated, accordingly, that while control circuits for only one drive unit have been shown, the control circuits for all other drive units may be similarly arranged, and 30 may, if desired, be caused to respond to a single starting switch US and a single stopping switch DS.

*Modified fluid pressure operated embodiments—
Figs. 11, 12, 13 and 14*

Referring to Figs. 11, 12 and 13, fluid pressure operated projecting and retracting mechanism is illustrated which may be used instead of the drive mechanism shown in detail in Figs. 7, 8 and 9. In Figs. 11 and 12, the drive mechanism comprises a fluid pressure operated ram 250, which may, except as hereinafter noted, be of entirely conventional construction. As illustrated, the ram is provided with a pair of piston rods 252 which project through the upper end of the ram cylinder and are connected together by a cross-bar 254. The cross-bar is also connected to a pair of spaced rods 256 which are inter-connected at their lower end by a cross-head 258, and may be 45 suitably guided in their up and down movements by the bar 257. The connection between the cross-head 258 and the drive shaft 110a, which may correspond in all respects to the previously 50 described drive shaft 110, comprises a cable 260, 55 which is trained over idler pulleys 262 and 264, and is suitably connected as by the member 266 to the cross-head 258. With this arrangement, it will be appreciated that upward movement of the cross-head 258 as viewed in Figs. 11 and 12 60 results in leftward movement of drive shaft 110a, and that downward movement of the cross-head 258 permits rightward movement of the drive shaft 110a. As previously described, the balancing mechanism associated with the shaft 110a 65 is preferably adjusted to substantially but not entirely counterbalance the weight of the barrier. Accordingly, if a barrier is released as by a downward movement of the cross-head 258, the barrier moves downwardly to the retracted position under 70 the influence of gravity.

In accordance with conventional practice, the ram 250 is provided with a pump motor 270, which may be arranged to drive a pump (not shown) arranged in the ram casing. The pump trans- 75

fers actuating fluid from the space above the ram piston (not shown), to the space below the ram piston in order to effect a raising movement of the cross-head 258; and permits a re-transfer of this fluid in order to permit a lowering movement of the ram. In accordance with conventional practice, the pumps usually used are of the centrifugal type, and permit the re-transfer upon being stopped.

The latch mechanism comprises a pivotally supported arm 274, urged to the illustrated position by a compression spring 276. In the illustrated position, a seat 278 formed on arm 274 is disposed in the path of the cross-head 254. The under-side 280 of the cam face 278 is undercut so that as the cross-head 254 moves upwardly it may cam the arm 274 in a counter-clockwise direction, in order to permit the cross-head 254 to pass above the seat 278.

The arm 274 is provided with a supplemental cam member 282, pivotally connected thereto as by a pin 284, and having an angularly formed cam face 286. A spring 288 connected between the member 282 and the arm 274 urges the member 282 to the illustrated position. Normally the face 286 projects beyond or to the left of the face 278, so that as the cross-head 254 moves upwardly, it engages the portion 286 and cams the member 282 in a clockwise direction against the force of the spring 288. This camming movement moves the portion 286 out of co-operative relation to the seat 278, and permits the cross-head 254 to seat upon the seat 278.

The cross-head 254 is also preferably provided with a switch actuating arm 290, which co-operates with a throw-over switch 292 to effect the stopping of the pump motor 270 at the intermediate position of the barriers.

Fig. 14 illustrates a control system which may be used to effect the starting of the pump motor 270; the temporary stopping thereof at the intermediate or warning position; and the final stopping thereof at the fully projected position. In Fig. 14 the starting is controlled by a manually operable switch US' which may be closed to start the projecting movement; retained in the closed position until such time as retracting movement of the mechanism is desired; and then opened to initiate such retracting movement. The remaining details of the system may best be understood with reference to the description of the operation as a whole of the system.

Closure of switch US' completes a circuit for the switch R1' which extends from the positive line conductor through the switch US', through throw-over switch 292 (which occupies the illustrated upper position under the conditions stated) and thence through the coil of reversing switch R1' to the negative line conductor. Upon completion of this circuit reversing switch R1' closes its contact R1'a' and completes armature and field contacts for the motor 270. These armature and field contacts are illustrated as being simultaneously closed in order to simplify the drawings, it being appreciated that in practice suitable control mechanism may be provided in a well known manner to insure completion of the field circuit prior to completion of the armature circuit. Upon completion of the just mentioned armature and field circuits motor 270 places the pump (not shown) in operation transferring the actuating fluid from the upper portion of the ram casing to the portion thereof beneath the ram piston, and causing the cross heads 254 and 258 to move upwardly. This upward movement, as previously

stated, pulls the slide shaft 110a to the left as viewed in Fig. 12 and brings about a projecting movement of the barriers connected thereto.

During the course of the projecting movement and as the barriers approach a position corresponding to the warning position thereof, the cross-head 254 engages the under-side 280 of the arm 274 and cams it in a counter-clockwise direction in order to permit the cross-head 254 to pass beyond it. As the upward movement of the cross-head 254 continues still further, cross-head 254 engages the nose 286 of the cam plate 282 and swings it in a crosswise direction relative to the arm 274 to a position in which it does not interfere with the movement of cross-head 254 and the seating relation to the seat 278. As the cross-head 254 passes above the seat 278 and while cam plate 282 is out of interfering relationship, the spring 276 is rendered effective to swing seat 278 under and in supporting relation to the cross-head 254.

The last mentioned relation of parts is attained just prior to the movement of arm 290 and the operative relation to the throw-over switch 292. This latter action throws switch 292 from the position shown in Fig. 14 to the lower position thereof, interrupting the original energizing circuit for the coil of the reversing switch R1' and preparing a re-energizing circuit therefor. This re-energizing circuit is subject to the contacts Ta' of the time relay T'. As described with reference to Fig. 10 time relay T' is provided with suitable timing delay mechanism which delays the closure of contacts Ta' until a predetermined interval after the arrival of the barriers at the warning position. At the time in question, accordingly, contacts Ta' are still open.

The interruption of the original energizing circuit for the reversing switch R1' brings the pump motor 270 to rest, rendering the pump ineffective to cause a further lifting movement of the cross-heads 254 and 258, and bringing the barriers to rest at the warning position. In view of the previously stated conventional ram construction the stopping of the pump motor may be expected to, in itself, permit a return movement of the ram. This return movement, however, is prevented, since the cross-head 254 is now firmly supported by the seat 278.

At the expiration of the previously mentioned timing interval, time relay T' closes the contact Ta' and re-completes an energizing circuit for the reversing switch R1' which thereupon restarts the motor 270, continuing the projecting movement of the barriers.

The arrival of the barriers at the fully projected position is preferably timed to accompany the arrival of the ram piston at its upper limit of travel. The arrival of the ram piston at its upper limit of travel brings the ram and consequently the barriers to rest. It may be expected that the barriers are required to remain in the fully projected position for only limited periods of time and, accordingly, to simplify the control system it is preferred to allow the pump to remain in operation during such periods. This action renders the pump effective to retain the ram in its fully projected position.

When it is desired to effect a retracting movement of the barriers the switch US' may be moved to the open position interrupting the circuit for the reversing switch R1' and stopping the motor 270 and the associated pump. Upon being stopped the pump permits a return circulation of the actuating fluid, and consequently permits the cross-

heads 254 and 258 to resume the lower limit positions thereof under the influence of gravity. The downward movement of the cross-heads 258 and 254 under gravity is accompanied as previously stated by a gravity return movement of the barriers connected thereto.

During the course of the downward movement of the cross-head 254 it engages the face of the cam plate 282 which action cams this member 10 and arm 274 in a counter-clockwise direction and permits the cross-head 254 to pass by the latch mechanism without interference. The latch mechanism is thus effective to co-operate with the cross-head 254 to control the ram movement 15 only during the projection operation. The arrival of the barriers at the retracting positions is preferably timed to accompany the arrival of the ram 250 at its lower limit of travel in which retracted positions the parts remain at rest until 20 a subsequent re-closure of the starting switch US.

As in the case of the control system of Fig. 10 it will be appreciated that the ram 270 is individual to the barriers at each side of an intersection or crossing and that a control system similar to that shown in Fig. 14 may be provided for each such ram.

Although specific embodiments of the present invention have been described, it will be appreciated that various modifications in the form, number and arrangement of parts may be made within the spirit and scope thereof.

What I claim is:

1. In a control system for a protective device embodying a retractable and projectable barrier, a motor operatively connected to said barrier, and a controller for said motor effective to cause said motor to start in operation, actuate said barrier to an intermediate height, stop said motor for a predetermined period, and then cause said motor to start and actuate said barrier to a fully projected position.

2. In a control system system for a protective device embodying a selectively retractable and projectable barrier, a motor operatively connected to said barrier, means placing said motor in operation to actuate said barrier to a projected position, and a controller associated with said motor for interrupting the movement of said motor for a predetermined period when said barrier is in a predetermined intermediate position and for causing said motor to continue said barrier movement toward said projected position at the expiration of said period.

55 3. In a control system for a protective device embodying a selectively retractable and projectable barrier, a motor operatively connected to said barrier, means placing said motor in operation to actuate said barrier to a projected position, and a controller actuated in accordance with the movement of said motor for causing said motor to stop and remain at rest for a predetermined period when said barrier reaches a predetermined intermediate position and for causing said motor 60 to continue said barrier movement toward said projected position at the expiration of said period.

4. In a control system for a protective device embodying a selectively retractable and projectable barrier, a motor operatively connected to said barrier, means placing said motor in operation to actuate said barrier to a projected position, and a controller for said motor effective to cause said motor to stop and remain at rest for a predetermined period when said barrier reaches a predetermined intermediate position and for causing 75

said motor to continue said barrier movement toward said projected position at the expiration of said period.

5. In a protective system embodying a selectively projectable and retractable barrier, an electric motor operatively connected to said barrier, circuit connections for controlling a supply of power for said motor, a controller for said motor including first, second, and third contacts, said first controller contact being effective to cause said motor to start and move said barrier from a retracted to an intermediate projected position, said second controller contact being effective to cause said motor to start and move said barrier from said intermediate projected position to a fully projected position, and said third controller contact being effective to cause said motor to start and move said barrier from a projected position to the retracted position.

6. In a protective system embodying a selectively projectable and retractable barrier, an electric motor operatively connected to said barrier, circuit connections for controlling a supply of power for said motor, a controller for said motor including first, second, and third contacts, said first controller contact being effective to cause said motor to start and move said barrier from a retracted to an intermediate projected position, said second controller contact being effective to cause said motor to start and move said barrier from said intermediate projected position to a fully projected position, said third controller contact being effective to cause said motor to start and move said barrier from a projected position to the retracted position, and means rendering said motor effective to drive said controller to effect the actuation of said first, second, and third contacts.

7. In a control system for a protective device embodying a selectively projectable and retractable barrier, a motor for operating said barrier, relay mechanism for placing said motor in operation to start a projecting movement of said barrier, a controller for said motor for interrupting the motor operation when said barrier is at an intermediate predetermined elevation, and timing mechanism coacting with said controller and said relay mechanism for causing said motor to restart after the expiration of the predetermined interval and continue said projecting movement of said barrier.

8. In a control system for a protective device embodying a selectively projectable and retractable barrier, a motor for actuating said barrier between said positions, switching mechanism for effecting the starting of said motor and for stopping said motor when said barrier reaches an intermediate height, and timing mechanism for causing said motor to restart after the expiration of a predetermined interval and continue said projecting movement of said barrier.

9. A protective system comprising a selectively retractable and projectable barrier, means mounting said barrier for pivotal movement about a predetermined axis, an actuating shaft for said barrier extending substantially parallel to said axis, means for effecting axial movement of said shaft, and an operating connection between said shaft and said barrier including spring means disposed to permit lost motion between said barrier and said shaft.

10. A protective system embodying a selectively projectable and retractable longitudinally extending barrier, a shaft for actuating said barrier and disposed substantially parallel to the

length thereof, means for effecting axial movement of said shaft within said barrier, a spring connected between said barrier and said shaft for effecting a projecting movement of said barrier in response to movement of said shaft in one direction, and a second spring connected between said barrier and said shaft for effecting a retracting movement of said barrier in response to movement of said shaft in the other direction.

5 11. A protective system embodying a selectively projectable and retractable longitudinally extending barrier, a casing for receiving said barrier, a shaft for actuating said barrier and disposed substantially parallel to the length thereof, means for effecting axial movement of said shaft within said barrier, a spring means connected between said barrier and said shaft for effecting a projecting movement of said barrier in response to movement of said shaft in one direction, a second spring connected between said barrier and said shaft for effecting a retracting movement of said barrier in response to movement of said shaft in the other direction, and additional spring mechanism connected between said barrier and 10 said casing for counter-balancing the weight of said barrier.

15 12. In a protective system, a barrier, means for supporting said barrier for movement between a projected position and a retracted position, means acting between said barrier and said supporting means for urging said barrier to the projected position, and additional means disposed to apply an initial abnormal actuating force to said barrier to start the same from the retracted position.

20 13. In a protective system, a barrier, means for supporting said barrier for movement between a projected and a retracted position, continuously acting means acting between said barrier and said supporting means for urging said barrier toward the projected position, means including a drive member connected to said barrier for moving said barrier, and additional means actuated by said drive means for supplementing the effect of said continuously acting means to break said barrier loose from the retracted position.

25 14. In a protective system, a barrier, means for supporting said barrier for movement between a projected and a retracted position, continuously acting means acting between said barrier and said supporting means for urging said barrier toward the projected position, means including a drive member connected to said barrier for moving said barrier, and means including a cam actuated by said drive means and co-acting with said barrier to break said barrier loose from the retracted position.

30 15. In a protective system, the combination of a retractable and projectable barrier, a source of power for said barrier actuatable to move said barrier from the retracted position toward the projected position, and control means associated with said source of power for interrupting said projecting movement at an intermediate point thereof for a predetermined interval, said control means being arranged to enable said source of power to continue said projecting movement at the expiration of said interval, and said source of power being arranged to apply a holding force to said barrier to retain said barrier to retain said barrier at said intermediate point during said interval.

35 16. In a protective system, the combination of a retractable and projectable barrier, a source of power for said barrier actuatable to move said barrier from the retracted position toward the projected position but arranged to permit a depressing movement of said barrier upon the application of an undue force thereto, and control means associated with said source of power for stopping said source of power for a predetermined 40 interval, said control means being arranged to permit a depressing movement of said barrier upon the application of an undue force thereto, and control means associated with said source of power for stopping said barrier for a predetermined interval at an intermediate point in said projecting movement and for restarting said movement at the expiration of said interval, said source being effective to maintain said barrier at said intermediate point during said interval except upon the application of said force.

45 17. In a protective system, the combination of a retractable and projectable barrier, a source of power for said barrier actuatable to move said barrier from the retracted position toward the projected position, connections between said source of power and said barrier arranged to permit a depressing movement of said barrier against the force of said source upon the application of an undue force to said barrier, control means associated with said source for stopping said barrier for a predetermined interval at an intermediate point in said projecting movement and for restarting said movement at the expiration of said interval, said source being effective to maintain said barrier at said intermediate point during said interval except upon the application of said force.

50 18. In a protective system, the combination of a retractable and projectable barrier, a source of power for said barrier actuatable to move said barrier from the retracted position toward the projected position, connections between said source of power and said barrier arranged to permit a depressing movement of said barrier against the force of said source upon the application of an undue force to said barrier, control means associated with said source for stopping said barrier for a predetermined interval at an intermediate point in said projecting movement and for restarting said movement at the expiration of said interval, said source being effective to maintain said barrier at said intermediate point during said interval except upon the application of said force, and means actuated in accordance with the operation of said source for actuating said control means.

55 19. In a protective system, the combination of a retractable and projectable barrier, a source of power for said barrier actuatable to move said barrier from the retracted position toward the projected position, and control means associated with said source of power for stopping said source of power for a predetermined interval when said source of power reaches a position corresponding to an intermediate point in said projecting movement, said control means being arranged to cause 60 said source of power to restart and continue said barrier movement at the expiration of said interval, and said source of power being arranged to apply a holding force to said barrier to retain said barrier at said intermediate point during 65 said interval.

70 20. In a protective system, the combination of a retractable and projectable barrier, a source of power for said barrier actuatable to move said barrier from the retracted position toward the projected position but arranged to permit a depressing movement of said barrier upon the application of an undue force thereto, and control means associated with said source of power for stopping said source of power for a predetermined 75 interval, said control means being arranged to permit a depressing movement of said barrier upon the application of an undue force thereto, and control means associated with said source of power for stopping said source of power for a predetermined

interval when said source of power reaches a position corresponding to an intermediate point in said projecting movement, said control means being arranged to cause said source of power to restart and continue said barrier movement at the expiration of said interval, and said source of

power being effective to retain said barrier at said intermediate point during said interval except upon application of said undue force to said barrier.

WILLIAM G. MILLER.
